UNITED STATES PATENT OFFICE.

EDWARD J. BRANDT, OF WATERTOWN, WISCONSIN, ASSIGNOR TO
COMPANY, OF CHICAGO, ILLINOI.

COIN-DELIVERY MACHINE.

1,143,685.

Specification of Letters Patent. Patented June 22, 1915.

Application filed August 21, 1914. Serial No. 857,878.

To all whom it may concern:

Be it known that I, EDWARD J. BRANDT, a citizen of the United States, and resident of Watertown, in the county of Jefferson 5 and State of Wisconsin, have invented certain new and useful Improvements in Coin-Delivery Machines; and I do hereby declare that the following is a full, clear, and exact description thereof.

Referring to coin-delivery machines of the "Brandt automatic cashier" type, the present invention has for its object to provide a simple, economical and efficient change-making machine that may be organized to pay coins of one denomination singly from any one of a series of coin-tray compartments and in multiple from two or more of said compartments, or to pay coins of different denominations, singly or in combinations; said invention consisting in what is herein particularly set forth with reference to the accompanying drawings and pointed out in the claims of this specification.

Figure 1 of the drawings represents a cross-section of the machine indicated by line 1—1 in Figs. 2 and 3; Fig. 2, a rear elevation partly in section, indicated by line 2—2 in Fig. 1; Fig. 3, a cross-section indicated by line 3—3 in Fig. 1, and showing parts broken away; Fig. 4, a plan view of the machine, and Fig. 5, a partly horizontal sectional view of a fragment of the machine indicated by line 5—5 in Fig. 1.

Referring by numerals to the drawings, 6 indicates each of paired front and rear legs supporting a base 7 having an upwardly extending front flange 8 and similarly disposed front corner-blocks 9, said 40 base, flange and blocks being preferably a single casting. Mounted on the base are side standards 11 having rearwardly extending ears 11' constituting supports for a fixed arbor 12, and loose on the arbor is 45 a series of elbow levers 13 having normally vertical branches thereof opposed to hangers 14 loose on a rod 16 supported in the upper ends of the standards.

Fastened on the base-flange 8 and blocks 50 9 is a plate 17 preferably provided with a series of angular notches open at the rear, and supported on the plate is a compartment coin-tray 18 generally similar to those now common in machines of the type afore-

said. A lower right-angle member 19 of the 55 coin-tray is provided with the usual intersecting rear and bottom slots that register with the notches in the plate 17 and in which the coin-pushers 21 of the machine are guided. The foot of the angle member 60 of the coin-tray is provided with transverse recesses in which levers 22 are fulcrumed, and a prong 22' of each lever extends up through an opening provided in said foot in the path of coin (not shown) in a compartment of said tray. A wedge-end of each lever engages a flaring edge-notch of a shank 23' of a gate 23 that is guided in a vertical pocket of the angle-member of the coin-tray, and no coin being opposed to the 70 lever prong 22', the gate is, by gravity, in the path of a coin-pusher, otherwise the weight of the coin actuates said lever to lift said gate clear of the coin-pusher.

In pivotal connection with the rear of the 75 front flange of the base are fingers 24, each having a rear eye-lug 26, and a spiral-spring 27 is connected at its ends to the eye-lugs of each pair of said fingers. The fingers extend up through slots in the plate 17, and 80 are yielding in the path of the lowermost coin being discharged from compartments of the coin-tray, but when the column of coin in any compartment is reduced to two and there is a tendency of the one uppermost to tilt and follow the under one on its discharge, the recoil of a pair of said fingers takes place in time to retain the last coin in 85 said tray-compartment.

Hung in connection with the standards 90 11 is an angular bail 28, the horizontal portion of which is a universal bar forward of the hangers 14, and a spiral-spring 29 connects an eye-lug 28' of the bail with a post 95 30 having a foot thereof fastened on the base aforesaid. The normally horizontal branch of each elbow lever 13 is opposed by a spring-controlled key-plate 31, the vertically disposed shank of which is guided in parallel plates 32, 33, fastened to spacing- 100 rods 34, and the uppermost of these plates serves as a member of the machine casing, which also includes a back-plate 35, side plates 36 and a combined back and top plate 37.

Each coin-pusher 21 is pivoted in a lower 105 forward extension 14' of a hanger 14, and the hanger-extension is provided with a for-

ward vertical socket containing a spiral-spring 38 opposed to the under side of said pusher.

Each of a series of wings 39 extend from the lower branch of one of a pair of the levers 13 to in rear of the lower branches of the next adjacent pair of said levers, and thus provision is had for actuating a combination of the hangers 14 and the coin-pushers 21 therewith by depressing a single one of the key-plates 31. Shoulders of the key-plates, in normal position, are stopped against the guide plate 33, and the shanks of said key-plates are in two rows, the push-buttons of the front row being preferably indexed to indicate different coin values, according to the paying scheme of the machine, and said buttons may be of a contrasting color to those in the rear row with which they are staggered.

The organization of the machine, as shown, is such that five cent coins are paid from the several compartments of the coin-tray, and the key-buttons in the front row are indexed 5, 10, 15, 20 and 25 respectively, reading from left to right, to denote unit value and multiples of the same. If key 5 be actuated, a single coin will be paid from the left hand compartment of the coin-tray. However if key 10, 15, 20 or 25 be actuated two, three, four or five coins will be paid singly from as many compartments of said tray according to the key depressed, and providing no coin-pusher of a combination is blocked against forward movement by a gate 23, the combinations of said coin-pushers being a result of the arrangement of the lever-wings 39 aforesaid.

If payment by a combination of the coin-pushers is blocked, coins may be paid singly from the left hand compartment of the coin-tray by an operation of the front key 5, or the key in rear thereof, or by the operation of any of the other rear keys, provided there is no gate obstruction to the coin-pusher associated with any one of said keys, both levers 13 of the left hand pair and one in each of the other pairs being capable of independent action against an opposing hanger 14 to which a single coin pusher is attached.

The spring-controlled universal bail-bar 28 automatically returns an actuated hanger or hangers and the opposing lever or levers to normal position when a depressed key is released, and the key is returned to its normal position by a controlling spring 40. Other springs 41 are arranged to have tension against the hangers 14 and thus insure of a full recoil of the same against the fulcrums of the opposing levers.

As a matter of detail, the upper ends of the hangers are forked as shown in Fig. 2, and the springs 41 are coiled on the rod 16 in the hanger-forks. It is also preferable to employ spacers 42 on the rod 16 between

hangers and between the end hangers and the standard supporting said rod.

The coin-receiving chute 43 of the machine and its reciprocal trap-door 44 are features now of common knowledge in "Brandt automatic cashiers".

I claim:

1. In a coin-delivery machine, a coin-tray provided with guide-slots for coin-pushers and having an angle-member provided with vertical pockets, levers fulcrumed in the tray and having end-prongs that extend under coin deposited in compartments of the tray, and gravity gates that are guided in said pockets and engaged by the levers to be lifted thereby under the weight of said coin clear of said coin-pushers to which they are opposed when the tray-compartments are empty.

2. In a coin-delivery machine, a coin-tray provided with guide-slots for coin-pushers, levers fulcrumed in the tray and having end-prongs that extend under coin deposited in compartments of the tray, and gravity gates in said tray having flaring edge-notches engaged by wedge-ends of the levers to be lifted by said levers under the weight of said coin clear of said coin-pushers to which they are opposed when the tray-compartments are empty.

3. In a coin-delivery machine, a fixed supporting member, a series of fingers pivotally connected to the supporting member, and springs connecting the fingers in pairs, each pair being yielding in the path of the lower-most coin having discharge from a tray-compartment of the machine.

4. In a coin-delivery machine, a base having a front upper flange, a series of fingers pivoted on the rear of the flange, a horizontal plate over said flange having slots through which the fingers extend in the path of coins to be discharged from the machine, and spiral-springs connecting said fingers in pairs.

5. In a coin-delivery machine, a series of pivotal hangers each having a spring-controlled pivotal coin-pusher therewith, elbow levers each having a lower branch thereof in opposition to a hanger, a series of wings each of which extends from said branch of one lever in opposition to the similar branch of an adjacent lever, a spring-controlled reciprocal key opposing the upper branch of each lever, and a spring-controlled swing-bar in the working path of the hangers.

6. In a coin-delivery machine, a series of pivotal hangers each having a spring-controlled pivotal coin-pusher therewith, elbow levers in pairs of which each pair has lower branches thereof in opposition to a hanger, a series of wings each of which extends from the lower branch of one of a pair of the levers in opposition to similar branches of the next adjacent pair of said levers,

spring-controlled reciprocatve key opposing the upper branch of each lever, and a spring-controlled swing-bar in the working path of the hangers.

7. In a coin-delivery machine, a series of independently spring-controlled pivotal hangers each having a pivotal spring-controlled coin-pusher therewith, elbow levers each having a lower branch thereof in opposition to a hanger, a series of wings each of which extends from said branch of one lever in opposition to a similar branch of an ad-

jacent lever, a spring-controlled reciprocatve key opposing the upper branch of each lever, and a spring-controlled swing-bar in 15 the working path of the hanger.

In testimony that I claim the foregoing I have hereunto set my hand at Chicago, in the county of Cook and State of Illinois, in the presence of two witnesses.

EDWARD J. BRANDT.
